US00D624923S

(12) **United States Design Patent**
Lu

(10) **Patent No.:** US D624,923 S
(45) **Date of Patent:** ** Oct. 5, 2010

(54) **HOUSING FOR A PORTABLE MEMORY DEVICE**

(75) Inventor: **Chen-Yin Lu**, Tainan (TW)

(73) Assignee: **Kingston Technology Corporation**,
Fountain Valley, CA (US)

(**) Term: **14 Years**

(21) Appl. No.: **29/316,746**

(22) Filed: **Oct. 28, 2009**

(51) **LOC (9) Cl.** 14-02

(52) **U.S. Cl.** **D14/480.5**

(57) **CLAIM**

The ornamental design for the housing for a portable memory device, as shown and described.

DESCRIPTION

FIG. 1 is a rear perspective view of a housing for a portable memory device showing my new design;

FIG. 2 is a top view thereof;

FIG. 3 is a left side view thereof;

FIG. 4 is a bottom view thereof;

FIG. 5 is a right side view thereof;

FIG. 6 is a rear view thereof;

FIG. 7 is a front view thereof;

FIG. 8 is a rear perspective view thereof, showing the design with the cap in the open position;

FIG. 9 is a top view thereof, showing the design with the cap in the open position;

FIG. 10 is a left side view thereof, showing the design with the cap in the open position;

FIG. 11 is a bottom view thereof, showing the design with the cap in the open position;

FIG. 12 is a right side view thereof, showing the design with the cap in the open position;

FIG. 13 is a rear view thereof, showing the design with the cap in the open position; and,

FIG. 14 is a front view thereof, showing the design with the cap in the open position.

The broken lines showing the connector feature are for the purpose of illustrating environmental structure and form no part of the claimed design.
